METHOD OF AND SYSTEM FOR
DISPENSING LIQUEFIED FUELOwen L. Garretson, Bartlesville, Okla., assignor
to Phillips Petroleum Company, a corporation
of Delaware

Application June 22, 1942, Serial No. 448,023

6 Claims. (Cl. 62—1)

My present invention relates to improved apparatus for vaporizing a volatile liquefied fuel.

More specifically, my invention discloses an improved liquid feed system for utilizing liquefied petroleum gases, such as propane, butane, and mixtures thereof. In my system as herein disclosed, the fuel is stored in large tanks, preferably underground. The fuel is withdrawn from storage in the liquid form, in order to avoid the variation in composition and heating value which occurs when such fuels are withdrawn as vapors. The comparative virtues of liquid versus vapor withdrawal are well known to the art, both types of operation having been used extensively in the past.

In the past, however, the liquid feed type dispensaries have had a common drawback in the matter of vaporizing the liquid after withdrawal from the storage vessel. This is a particular obstacle where straight commercial or normal butane is to be used, because of the low vapor pressure (or, conversely stated, the high boiling point) of this particular hydrocarbon. The condition is of course most troublesome in localities where the climate is relatively cold. Early systems for this service have employed vaporizers heated by water from a gas-fired water heater. Other proposals, some of which were actually placed in operation, included extensive underground piping networks to absorb heat of the earth for vaporization; earth vaporizers augmented by circulating water from a city water system; atmospheric or air-heated vaporizer coils, sometimes placed in a heated dwelling or else in a separate vaporizer house. Each of the above methods of vaporizing have obvious disadvantages from the standpoints of equipment cost, excavating cost, personal hazard and often a combination of these factors.

My invention is a practical answer to the above outlined problem, as it employs the free heat of the earth for vaporization, and does it in a manner which is safe, efficient and economical of execution.

An object of my invention is to provide a most economical system for vaporization of a liquefied fuel gas.

It is a further object to provide a system of the above class which is entirely safe in operation.

It is an object to attain adequate vaporization capacity in such a system without resort to artificial heating means, or to extensive excavation for installation of heat absorbers.

Other objects and advantages will be recog-

nized from the following specification and the drawing forming a part thereof, in which:

Figure 1 is a schematic view in vertical section of one form of my invention, and Figure 2 is a transverse sectional view of a portion of Figure 1, taken about the line 2—2.

Referring now to Figure 1, the numeral 10 indicates a buried storage tank suitable for liquefied petroleum gases. The tank is equipped with the usual servicing and safety appliances, which may include a filler valve, a pressure relief valve, a liquid level gauge, etc. These appliances are indicated collectively by the numeral 11 and are not shown in detail, being apart from my disclosure. It is sufficient, for present considerations, to state that the accessories referred to are usually connected in a common riser as indicated by numeral 12, and are protected by a casing 13, the interior of which is accessible from ground level through a hinged or removable cover 14. The structure thus far described is, of itself, old and common in the art.

Within the tank 10, I provide a pair of riser pipes 15 and 16, which are joined at a point 25 outside the tank by a horizontal conduit 17. Connected to an opening in the top side of conduit 17 is a pressure regulator 18, provided with an outlet conduit 19. The outlet conduit passes through a suitable aperture in the housing 13, as at point 20, and enters the horizontal conduit at 21 and emerging at 22, from whence it proceeds eventually to the point of use. At or near such point of use, a second stage regulator (not shown) may be provided if desired.

35 The conduit 19 is located concentrically within the casing or conduit 17, forming a continuous and imperforate channel therein. The juncture of the conduits 17 and 19 at points 21 and 22 may be made by welding, by threaded 40 pipe fittings, bolted flanges, or whatever means may be most expedient and economical. The important consideration here is that two parallel pressure-tight channels be defined, with due provision made to prevent leakage between the channels or to the ground or other surrounding medium.

While a plain tube would serve in many cases, it is more conducive to good operation to provide longitudinal fins arranged radially about the portion of tube 19 which lies within the casing 17. Figure 2 illustrates the essential features of the fin arrangement. It is immaterial whether the fins are a part of the conduit 19 or of the casing 17; indeed they might be attached to both members, or the whole conduit assembly includ-

ing the radiating fins between points 21 and 22 could be formed of a single metal casting. Figure 2 illustrates the cast type of construction, in which the fins 24 are joined integrally with the conduit 19 and casing 17, forming a plurality of elongated chambers 25. It is understood that the fins 24 are to be either perforated or cut out entirely in the region of the extremities of casing 17, so that the risers 15 and 16 will have common access to all of the chambers 25.

In operation, the tank 10 is filled to a desired level (26-26) with a liquefied gas such as butane, for example. Upon the first such filling, air and later a mixture of air and butane vapor will at first be withdrawn from the line 19. Upon continued purging of the air and butane vapor, liquid butane will shortly rise in the pipes 15 and 16, and will gain admittance to the regulator 18 through the casing 17.

For normal operation subsequent to the first filling, the regulator 18 is set to deliver an outlet pressure of some 3 to 6 p. s. i. to the line 19. At normal earth temperatures (which may vary between 40 and 75° F. in various localities), the vapor pressure of the stored butane will be in the range of 15 to 35 p. s. i. Thus, at very low rates of flow, the liquid will be substantially vaporized at the regulator orifice where pressure reduction occurs. At any higher flow, however, at least a substantial part of the fuel will pass through the regulator valve in liquid form and vaporization will proceed in the line 19. The resultant cooling of the liquid in process of vaporization will cause an exchange of heat between the content of line 19 and the surrounding liquid in casing 17, resulting in a cooling effect upon the latter liquid also.

Because of the change of density brought about by cooling the liquid in the casing 17, a thermosyphon action is induced, since the heavy, cooled liquid will seek a lower level and warm, lighter liquid will seek to rise and replace the cool portion. The direction of circulation in the casing 17 and the appended riser pipes 15 and 16 is of no practical consequence, but it is nevertheless evident that circulation will occur in the direction indicated by the arrows in Figure 1. This statement is based upon observations of many types of coil vaporizers, in which it has been noted that the colder portion of the coil is near the inlet end of the coil. Thus the liquid at the left end of the heat exchange casing 17 will normally be more dense than that at the right hand end, and this state of conditions is conducive to a circulation in the indicated direction.

The continuous circulation of liquid above described serves the purpose of bringing all of the stored liquid into heat exchange contact with the portion which is being vaporized. Thus the heat content of the whole stored mass of liquid is made available for vaporization of the portion to be used. Meantime, heat is transferred from the earth to the stored liquid, through the walls of the tank 10, and the heat lost to the vaporizing process is continually replenished. Undue refrigeration of the stored fuel is thus prevented and a high enough vapor pressure for satisfactory operation is assured.

Various modifications can be devised, all within the scope of my invention. I also contemplate the use of additional vaporizer means beyond the

outlet of my improved storage tank vaporizer in installations where extremely adverse conditions of use render such auxiliary devices necessary. The primary utility of my device, however, lies in the fact that the structure disclosed is adequate for most normal usage, and the expense of providing artificially heated or other auxiliary vaporizers is thus obviated except in very extreme service.

I claim:

1. In a fuel dispensing system of the class described which includes a storage tank for liquefied fuel: a thermosyphon circuit associated with the storage tank which is comprised of a liquid riser, a liquid return and a communicating conduit therebetween forming a circuit; a pressure regulator associated with said circuit and adapted to tap off a portion of the content thereof at a reduced pressure; a conduit for returning the said portion in heat exchange relationship with the said circuit.

2. A fuel dispensing system for liquefied gas which comprises a storage tank for the liquefied fuel, a first conduit for setting up a circulation of the liquid, the opposite ends of the said conduit extending below the surface of the liquid, a second conduit for withdrawing fuel from said first conduit, pressure reducing means in said second conduit, the low pressure side being in heat exchange relationship with the first conduit.

3. A fuel dispensing system for liquefied gas which comprises a storage tank for the liquefied fuel, a first conduit for setting up a circulation of the liquid, the opposite ends of the said conduit extending below the surface of the liquid, a second conduit for withdrawing fuel from said first conduit, pressure reducing means in said second conduit, said conduits being concentrically arranged.

4. The method of dispensing and vaporizing liquefied gas from a quantity of liquid gas in a storage member comprising circulating the liquid gas by thermosyphon forces through a conduit, drawing off the gas from an upper point in the conduit, expanding the gas, and passing the expanded gas in heat exchange relation to the conduit to increase the thermosyphon forces and to accelerate the thermosyphon circulation.

5. A fuel dispensing system comprising a storage tank for liquefied fuel, an inverted U-shaped conduit disposed with one leg of the U in communication with the tank adjacent the bottom of the tank, and the other leg of the U in communication with the tank at a point above the point of communication of the first leg but in the lower half of the tank, a dispensing line connected to the conduit at an upper portion thereof, and passing in heat exchange relation therewith, and a pressure reducing valve in said line at a point before the line passes in said heat exchanging relation to said conduit.

6. A fuel dispensing system comprising a storage tank for liquefied fuel, an inverted U shaped conduit disposed with one leg of the U in communication with the tank adjacent the bottom of the tank, and the other leg of the U in communication with the tank at a point above the point of communication of the first leg but in the lower half of the tank, a dispensing line connected to the conduit at an upper portion thereof, and a pressure reducing valve in said line.

OWEN L. GARRETSON.
